UNITED STATES PATENT OFFICE.

MILDRED E. SHUGG, OF BROOKLYN, NEW YORK.

DESIGN FOR A TOY.

54,963.

Specification for Design.

Patented Apr. 20, 1920.

Application filed October 6, 1919. Serial No. 328,915. Term of patent 14 years.

To all whom it may concern:

Be it known that I, MILDRED E. SHUGG, a citizen of the United States, and a resident of the city of New York, borough of Brooklyn, in the county of Kings and State of New York, have invented a new, original, and ornamental Design for a Toy, of which the following is a specification.

Reference is to be had to the accompanying drawings, in which—

Fig. 2 is a front elevation thereof.

I claim—

The ornamental design for a toy as shown.

MILDRED E. SHUGG.
